UNITED STATES PATENT OFFICE.

GEORGE LOWE, OF PHILADELPHIA, PENNSYLVANIA, ASSIGNOR TO
THOMAS SWANN, OF SAME PLACE.

DESIGN FOR MIRROR FRAMES AND STANDS.

Specification forming part of Design No. 7,917, dated December 8, 1874; application filed July 11, 1874.
[Term of Patent 7 years.]

To all whom it may concern:

Be it known that I, GEORGE LOWE, of Philadelphia, Pennsylvania, have invented a Design for a Looking-Glass Frame or Stand, of which the following is a specification:

The figure in the accompanying drawing represents a looking-glass frame, stand, and base made in accordance with my design.

The looking-glass frame A is rounded at the top and bottom, has a smooth exterior and an inner scalloped edge, a, and is ornamented at the top by a cap-piece, b, on which is a head in relief. The said frame is also ornamented at the sides by "Maltese crosses," and at the bottom by a panel containing a foliated figure, as shown in the drawing. The frame B is secured to the base at d, has foliated and other ornaments, e, at the bottom, and uprights or side pieces ornamented by brackets f, on which are parrots or other birds, h, the end of each upright corresponding in outline to a lily. The base D has foliated corner-pieces i and a

dished front piece, j, and is otherwise ornamented in a manner so clearly shown by the drawing as to render minute description unnecessary.

I claim—

1. The design for the looking-glass frame having rounded ends, a cap-piece, b, and a lower panel, as shown and described.
2. The design for the supporting-frame, ornamented by birds, scrolls, and other figures and forms, as shown.
3. The design for the ornamental base, having inclined faces, scored edges, and foliated corner-pieces, as set forth.

In testimony whereof I have signed my name to this specification in the presence of two subscribing witnesses.

GEORGE LOWE.

Witnesses:

WM. A. STEEL,
HARRY SMITH.
